UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,734, dated July 2, 1901.

Application filed June 6, 1901. Serial No. 63,470. Term of patent 7 years.

To all whom it may concern:

Be it known that I, WILLIAM T. SMITH, a citizen of the United States, residing in Philadelphia, Pennsylvania, have invented and produced a certain new and original Design for a Woven Fabric, of which the following is a specification.

My design is shown in the accompanying drawing, which represents sufficient of the pattern to illustrate the design, the remainder of the pattern being merely a repetition of what is shown.

The design comprises the figures 1 and 2 and a border 3, the intervening groundwork having representations of birds and stags' heads. Each of the figures 1 and 2 comprises a central ornament 4 on a ground having a

border composed of step-like parallel bands 5, and the border 2 has inwardly-projecting rectangular members 6.

Having thus described my invention, I claim and desire to secure by Letters Patent—

The design for a woven fabric, substantially as described and as shown in the accompanying drawing.

In testimony whereof I have signed my name to this specification in the presence of two subscribing witnesses.

WILLIAM T. SMITH.

Witnesses:

HARRY BLOCK,
WM. H. MACMUNN.
